UNITED STATES PATENT OFFICE.

FREDERICK W. CAMMANN, OF DENVER, COLORADO, ASSIGNOR OF ONE-SIXTH TO CHARLES M. BICE, OF SAME PLACE.

HAT-FASTENER.

SPECIFICATION forming part of Letters Patent No. 645,521, dated March 13, 1900.

Application filed July 16, 1898. Serial No. 686,163. (No model.)

To all whom it may concern:

Be it known that I, FREDERICK W. CAMMANN, a citizen of the United States of America, residing at Denver, in the county of Arapahoe and State of Colorado, have invented certain new and useful Improvements in Hat-Pin Fasteners; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in hat-pin fasteners, and comprises means for guiding the point of the pin and locking the latter securely in place when adjusted, my object being to provide a device of this class 20 which shall be simple in construction, economical in cost, and reliable, durable, and efficient in use; and to these ends the invention consists of the features hereinafter described and claimed, all of which will be fully understood by reference to the accompanying drawings, in which is illustrated an embodiment thereof.

In the drawings, Figure 1 is a perspective view of my improved device shown in connection with a hat-pin. Fig. 2 is a section taken through a hat with the device applied, which is also shown in section, the pin being in place. Fig. 3 is a section taken through the device applied to a hat, the point of the 35 pin being shown to illustrate the guiding function of the device. Fig. 4 is a perspective view showing the elements of the device detached from one another.

Similar reference characters indicating corresponding parts in these views, let the numeral 5 designate a concave or funnel-shaped guide having an opening at its bottom large enough to allow the pin 6 to pass through. Surrounding this bottom opening and attached exteriorly to the guide is a thimble 7, in which is located a piece 8 of rubber or other suitable elastic or yielding material adapted to grip the pin when passed therethrough. The rubber is pressed into the

thimble and retained in place by virtue of its 50 elasticity. Any other suitable means that may be found desirable may be employed for holding the rubber in place in case the elastic feature is not found ample for the purpose. The thimble is made somewhat longer than 55 the rubber, this extension being provided with slits to allow it to be turned down upon a washer 9, (see Figs. 2 and 3,) surrounding the thimble on the outside of the hat 10, through the fabric of which the thimble 60 passes. In applying the device to the hat the thimble 7 is passed through the fabric 10 from the inside, the funnel-shaped guide being on the inside. The washer 9 is then slipped over the protruding portion of the thimble and 65 pressed against the fabric of the hat on the outside, after which the slotted extension 7^a of the thimble is bent down upon the washer, locking it securely in place. The hat-band (not shown) is then placed over the device, 70 which is thereby concealed from the outside.

The device may be made plain and cheap or ornamental and expensive, as may be desired. In either case its utility will be the same.

In using the hat-pin the latter is inserted from the side of the hat opposite where the device is located. After the pin has passed through the hair of the head the point is directed by the funnel-shaped guide 5 into the 80 opening at the bottom of the guide and thence through the rubber lock 8. (See Fig. 2.) If desired, an eyelet may be placed on the side of the hat opposite where the device is located to facilitate the entrance of the pin and 85 prevent the injury to the hat on that side by insuring the insertion of the pin in the same place at all times.

Having thus described my invention, what I claim is—

In a hat-pin-fastening device, the combination with the pin, of a funnel-shaped guide having a bottom opening to allow the pin to pass therethrough, a thimble attached to the guide exteriorly and surrounding the pin-opening therein, a piece of elastic substance pressed into the thimble and arranged to maintain its position therein by its elasticity,

said substance normally closing the opening in the bottom of the guide, which is located inside the hat, the thimble being passed through the hat fabric, its outer extremity being open, a washer applied to the thimble extremity outside the hat, the thimble protruding through the opening in the washer, its extremity being slotted, turned outwardly

and bent down on the washer to hold the latter in place.

10

In testimony whereof I affix my signature in presence of two witnesses.

FREDERICK W. CAMMANN.
